UNITED STATES PATENT OFFICE

135,161

DESIGN FOR A POUR-OUT BOTTLE CAP

Herman Karl Stempel, Fort Madison, Iowa, assignor to W. A. Sheaffer Pen Company, Fort Madison, Iowa, a corporation of Delaware

Application February 14, 1942, Serial No. 105,790

Term of patent 7 years

To all whom it may concern:

Be it known that I, Herman Karl Stempel, a citizen of the United States, residing at Fort Madison, in the county of Lee and State of Iowa, have invented a new, original, and ornamental Design for a Pour-Out Bottle Cap, of which the following is a specification, reference being had to the accompanying drawing, forming a part thereof.

Figure 1 is a top plan view of a pour-out bottle cap showing my new design;

Fig. 2 is a side elevational view of Figure 1; and

Fig. 3 is a front elevational view of Fig. 2.

I claim:

The ornamental design for a pour-out bottle cap, substantially as shown.

HERMAN KARL STEMPFL.
